RAIL BRACE

James H. Asselin, Winnetka, Ill.

Application February 24, 1948, Serial No. 144,702

Term of patent 14 years

(Cl. D66—3)

To all whom it may concern:

Be it known that I, James H. Asselin, a citizen of the United States, residing at 845 Lincoln Avenue, Winnetka, in the county of Cook and State of Illinois, have invented a new, original, and ornamental Design for a Rail Brace, of which the following is a specification, reference being had to the accompanying drawings, forming part thereof, and in which:

Fig. 1 is a perspective view of a rail brace showing my new design;

Fig. 2 is a top plan view;

Fig. 3 is a front elevation;

Fig. 4 is a bottom plan view;

Fig. 5 is a rear elevation;

Fig. 6 is an end view looking toward the right hand side of Fig. 3, and

Fig. 7 is an end view of the other end looking toward the left hand end of Fig. 3.

I claim:

The ornamental design for a rail brace, as shown.

JAMES H. ASSELIN.
